(57) **CLAIM**

The ornamental design for a lens for light detection element as shown and described.

DESCRIPTION

FIG. 1 is a front view of a lens for light detection element of our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front perspective view thereof;

FIG. 8 is a rear perspective view thereof;

FIG. 9 is a sectional view taken along the line 9-9 of FIG. 1;

FIG. 10 is a sectional view taken along the line 10-10 of FIG. 1;

FIG. 11 is a sectional view taken along the line 11-11 of FIG. 1;

FIG. 12 is a sectional view taken along the line 12-12 of FIG. 1; and,

(Continued)

FIG. 13 is an enlarged view showing a portion of FIG. 9 defined by lines 13-13 and 13'-13'.

1 Claim, 13 Drawing Sheets
